(57) **CLAIM**

The ornamental design for a foldable stand, as shown and described.

DESCRIPTION

FIG. 1 is a top-front-left perspective view of a foldable stand showing my new design;

FIG. 2 is a bottom-rear-right perspective view thereof;

FIG. 3 is a front elevated view thereof;

FIG. 4 is a rear elevated view thereof;

FIG. 5 is a top plan view thereof;

FIG. 6 is a bottom plan view thereof;

FIG. 7 is a right elevated view thereof;

FIG. 8 is a left elevated view thereof;

FIG. 9 is a top-front-left perspective view thereof, showing the foldable stand in a storage configuration;

FIG. 10 is a bottom-rear-right perspective view thereof, showing the foldable stand in the storage configuration;

FIG. 11 is a reduced top-front-left perspective view thereof, showing the foldable stand in an unfolded configuration; and,

FIG. 12 is a reduced bottom-rear-right perspective view thereof, showing the foldable stand in the unfolded configuration.
